UNITED STATES PATENT OFFICE.

WILLARD DELMONT DOREMUS, OF WASHINGTON, DISTRICT OF COLUMBIA,
ASSIGNOR TO THE REX CIGAR VENDING COMPANY, OF WASHINGTON,
DISTRICT OF COLUMBIA, A CORPORATION OF VIRGINIA.

DESIGN FOR A CASE FOR VENDING-MACHINES.

SPECIFICATION forming part of Design No. 35,237, dated October 29, 1901.

Application filed August 3, 1900. Serial No. 25,842. Term of patent 14 years.

To all whom it may concern:

Be it known that I, WILLARD DELMONT DOREMUS, a citizen of the United States, residing at the city of Washington, District of Columbia, have invented and produced a new and original Design for a Case for Vending-Machines; and I do hereby declare the following to be a full, clear, and exact description of the same, reference being had to the accompanying drawing, forming a part thereof.

The object of my invention is to provide an attractive and useful casing for vending-machines; and it consists of a design for the configuration shown in the accompanying drawing, in which the figure is a perspective view of the casing in its entirety.

The peculiarity of the design or configuration of said casing lies chiefly in its varying form of cross-section.

The characteristic features of my design comprise a casing substantially rectangular in cross-section, having a widened or forwardly-extending base portion and upwardly-inclined sides, the upper portions thereof being of frame or sash-like construction. The front and rear edge portions, respectively, of the side walls comprehended between the base portion and the top have general lines of contour that meet in inclination at a central point to form an obtuse angle, while the lower front edge line thereof terminates in a swell or compound curve. The lids or lock-doors form the terminals, respectively, of the top and rear side, while both are provided with openings, as shown.

The front of the case is provided with a cross-bar or sash that extends between the respective side walls at a central point to provide a division of the front above the base into two openings.

Referring to the design in its leading and essential features by numerals, 2 and 3 are used to indicate the side walls, the upper portions of which at 4 are provided with openings or sashes that are raised to form plain

borders 5. The top and rear of the casing are respectively closed by hinged covers 6 and 7, the swinging edges of which are made to fit snugly to tightly close the top and rear side of the chamber, while 8 indicates the overlapping eye members of the lock-fastening. The respective side walls 2 and 3 are provided at the front and rear edges with angular lines of contour that meet centrally in an obtuse angle at 9 on the rear edges, respectively, but which terminate in a swell or compound curve at 10 on the front edges, respectively. The side walls are provided at the point 11 with a sash-bar 12, that is formed to provide a concavo-convex extension or flange 13. This bar divides the front of the case into two open portions 14 and 15. The extension 13 is provided with a centrally-disposed vertical recess or slot 16 and an elongated horizontal slot 17.

Minor features of the design are embraced as follows: The base portion is extended to form portions 18 and 19, while the ends thereof are connected by a front piece 20, that is provided with a top extension 21, that is adapted to project at right angles to form a top piece and that is provided with a rectangular opening 22. Immediately beneath said opening 22 is placed a platform 23, having a groove or depression that is arranged to extend as an arc portion of a curvilinear track 24, that terminates at one end with downwardly-inclined pieces 25, arranged in spaced parallelism.

Having described my invention, what I desire to claim is—

The design for a casing for vending-machines as herein shown and described.

In testimony whereof I affix my signature in presence of two witnesses.

WILLARD DELMONT DOREMUS.
